FRANK EARHART HARE, OF BOOTHBAY HARBOR, MAINE.

STARTING AND STOPPING DEVICE FOR PHONOGRAHS.

1,084,428.

Specification of Letters Patent. Patented Jan. 13, 1914.

Application filed February 1, 1913. Serial No. 745,611.

To all whom it may concern:

Be it known that I, FRANK E. HARE, a citizen of the United States, and a resident of Boothbay Harbor, in the county of Lincoln and State of Maine, have invented a new and Improved Starting and Stopping Device for Phonographs, of which the following is a full, clear, and exact description.

10 The invention relates to phonographs using disk records, and its object is to provide a new and improved starting and stopping device for such phonographs and similar machines and arranged to enable the 15 user of the machine to readily start the same and to permit of conveniently and quickly setting the device according to the record with a view to automatically stop the machine at the time the stylus reaches the end 20 of the groove in the record.

In order to accomplish the desired result, use is made of a stopping means to stop and release the turntable of the phonograph, a swing arm extending over the turntable and 25 the record held thereon, the swing arm being manually-controlled to allow of setting the swing arm in any desired position relative to the record, and a controlling means mounted on said swing arm and connected 30 with the said stopping means, the said controlling means being manually controlled for releasing the said stopping means to start the phonograph, and the said controlling means being adapted to be actuated by 35 the stylus on the sound box of the phonograph to release the said stopping means, and thereby stop the phonograph automatically.

A practical embodiment of the invention 40 is represented in the accompanying drawings forming a part of this specification, in which similar characters of reference indicate corresponding parts in all the views.

Figure 1 is a side elevation of the starting and stopping device as applied to a phonograph, parts being shown in section; Fig. 2 is a plan view of the same; Fig. 3 is an enlarged inverted plan view of the swing arm with its pivot shown in section; Fig. 4 is a cross section of the same on the line 4-4 of Fig. 3; and Fig. 5 is a perspective view of the brake for the turntable.

The phonograph on which the starting and stopping device is applied may be of any approved construction and mounted on a suitable frame or casing in which is jour-

naled a driven shaft B carrying the turntable C supporting the disk record D, in the groove of which is adapted to travel the stylus E of the sound box F for reproducing the sounds in the usual manner. The means carrying the sound box F and the horn or other means for delivering the reproduced sound into a room are not shown in the drawings, but they are of any approved construction so that further description of the same is not deemed necessary.

The stopping and starting device for releasing the turntable C or for stopping the same is arranged as follows: On the top 70 of the frame or casing A is mounted a spring brake G having a shoe G', of leather, felt or other suitable material, adapted to engage the under face of the turntable C to hold the same normally against rotation. 75 The free end of the spring brake G is provided with an arm G² engaged by one end H' of a tripping lever H fulcrumed at H² on the under side of a swing arm I having a hub I' mounted to turn on a pivot J 80 erected on a plate J' adjustably secured to the top of the frame or casing A by screws J² screwing in the frame of the casing A passing through elongated slots J³ arranged in the plate J', as plainly shown in Fig. 2, 85 The arm I extends over the turntable C and the disk record D held thereon, and the said swing arm I can be moved into any desired position by the operator, and in order to hold the swing arm I in the adjusted position use is made of a spring K coiled on the lower end of the pivot J and engaging the under side of the hub I'. The upper end of the hub I' is engaged by the head of a screw I² screwing into the pivot J so as to force 90 the hub I' in contact with the spring K with a view to increase or decrease the tension thereof and to thus hold the swing arm I in the position into which it is moved by 95 the operator.

The under side of the swing arm I is provided with spaced bearings I³, I⁴ in which is mounted to slide a rod L of spring wire or other similar material. The rear end of the rod L is provided with a depending offset L' engaging the upper end H³ of the tripping lever H to impart a swinging movement to the same on pulling the rod L forward, so that the spring brake G releases the turntable C to allow the latter to rotate. 105 The forward end of the rod L terminates in a handle L² under the control of the op-

erator for pulling the rod L forward whenever it is desired to release the brake, as above explained. The forward end of the rod L extends through an elongated bearing 5 I² held on the forward end of the swing arm I to allow this forward end of the rod L to slide forward and backward in the bearing I² and also to move sidewise therein, as will be readily understood by reference to 10 the full and dotted line positions shown in Fig. 3.

Near the forward end of the rod L is adjustably secured a block N by the use of set screws O, and from the block N extends sidewise 15 an arm N' on which is adjustably secured a head N² by the use of a clamping screw N³, the outer edge being approximately of a curvature corresponding to the shape of the last convolution of the groove 20 in the disk record, as plainly indicated in Figs. 2 and 3. The outer edge of the head N² is adapted to be engaged by the stylus E so that the latter imparts a swinging motion to the forward end of the rod L at the time 25 the stylus reaches the end of the groove in the disk record D. The arm N' is guided on a guide rod P attached to the swing arm I, the guide rod P also serving as a stop for limiting the inward movement of the stylus 30 toward the center of the disk record D. On the block N is adjustably secured a sidewise extending stop plate Q by the use of set screws Q', and this stop plate Q is adapted to abut with its inner edge on the forward 35 end of a stop plate R adjustably secured by screws R' to one side of the swing arm I, the screws R' passing through an elongated slot in the stop plate R to allow of adjusting the latter lengthwise on the swing arm I.

40 The operation is as follows: After the disk record D has been placed in position on the turntable C the operator swings the swing arm I over the disk record to a point near the center of the record, and then the operator pulls on the handle L² so that the 45 brake G releases the turntable C to allow the latter to rotate driven by the usual motor of the phonograph. The operator then swings the arm I outward until the outer edge of 50 the head N² is at the last convolution of the spiral groove in the disk record D, as plainly indicated in Fig. 2. On pulling the rod L forward as above described the inner edge of the plate Q moves into engagement with 55 the forward end of the stop plate R to hold the rod L locked in its forward position for the time being. When the piece has been played in the usual manner and the stylus E reaches the innermost convolution of the 60 groove in the disk record D then the said stylus engages the head N² and pushes the same toward the arm I whereby the plate Q moves out of engagement with the stop plate R thus unlocking the rod L and allowing the 65 same to move rearward owing to the action

of the spring of the brake G imparting a return swinging movement to the tripping lever H. It will be noticed that when the rod L is released and with it the tripping lever H, the brake G returns to normal position, that is, its brake shoe G' moves into contact with the under face of the turntable C to stop the latter.

From the foregoing it will be seen that by the arrangement described the brake G for 75 the turntable C is manually released at the time the rod L is drawn forward by the operator, but the brake is automatically applied by the action of the stylus E on the head N², as above explained.

The starting and stopping device shown and described is very simple and can be readily applied to phonographs and similar machines, as now constructed, and the swing arm I can be readily set according to the record used and irrespective of the radial distance from the end of the groove to the center of the disk record. It will also be noticed that the arm I can be set relative to the disk record at any point intermediate 90 the beginning and the end of the groove to automatically stop the machine at the time the stylus reaches such point.

The sweep of the swing arm I is preferably somewhat less than that of the reproducer arm and in order to insure that the stylus E strikes the outer edge of the head N² approximately at the same point each time the machine is used, it is necessary to set the center of the pivot J slightly to the 100 right of a radial line extending from the vertical axis of the reproducer arm to the center of the turntable C.

Having thus described my invention, I claim as new and desire to secure by Letters 105 Patent:

1. In a starting and stopping device, the combination with a turntable, and a traveling member, of a spring brake adapted to engage the turntable to stop or release the 110 same, a swing arm extending over the turntable, the swing arm being adapted to be swung by the operator to any desired position over the turntable, a tripping lever fulcrumed on the said swing arm and adapted 115 to engage the said brake to apply or release the same, a rod mounted on the said swing arm to move longitudinally and laterally and controlling the said tripping lever to release the said brake, a locking device for 120 locking the said rod in position on the swing arm at the time the said brake is released, and a head on the said rod and extending into the path of the traveling member to be actuated by the said member to unlock the rod and thereby permit the brake to be applied to stop the rotation of the 125 turntable.

2. In a starting and stopping device, the combination with a turntable, and a travel-

- ing member, of a spring brake adapted to engage the under face of the turntable to stop or release the said turntable, a swing arm extending over the said turntable, means for holding the swing arm in any desired adjusted position, a tripping lever fulcrumed on the said swing arm adjacent the pivotal end thereof, the said tripping lever engaging the said spring brake to apply or release the same, a rod mounted to slide on the said swing arm and provided at its rear end with an offset engaging the said tripping lever, the forward end of the rod being provided with a handle adapted to be engaged by the operator for moving the rod in the direction of its length to actuate the said tripping lever for releasing the said brake, 40 a block adjustably secured to the forward end of the said rod and provided with a side-wise extending arm terminating in a head 45 adapted to be engaged by the traveling member, a stop plate adjustably secured to the said block, and a stop on the said swing arm adapted to be engaged by the said stop plate.
5. In a starting and stopping device, the combination with a turntable, and a traveling member, of a spring brake adapted to engage the under side of the turntable and provided with an arm, an arm adapted to swing over the turntable, a pivoted tripping lever mounted on the pivoted end of the arm and engaging the arm of the brake, a spring rod mounted to slide on the under side of the swinging arm and provided with an arm engaging the tripping lever, the 55 outer end of the rod being adapted to be swung laterally, means for locking the said rod in position when drawn out and swung laterally, and a member carried by the outer end of the rod and adapted to be engaged by 60 the said traveling member.
6. In testimony whereof I have signed my name to this specification in the presence of two subscribing witnesses.
